UNITED STATES PATENT OFFICE.

WALTER J. CHRISTIE, OF ALAMEDA, CALIFORNIA.

CASTING MACHINE.

Application filed December 1, 1922, Serial No. 604,277. Renewed November 1, 1926.

The invention relates to improvements in machines for making castings, and in particular to that type of machine employing metallic mold members in conjunction with 5 metallic or sand cores, or without any cores.

Present machines of this character, I observe, are deficient in durability and positiveness of operation because of the continuous warping of the molds, also, certain 10 parts of the metallic molds are prone to burn out prematurely, thus producing finned and imperfect castings which necessitates rejecting them as defective or unacceptable to the trade.

15 To overcome the above objections is among my objects. Other objects of importance, include, the provision of a bipartite mold having means to prevent the warping of its members, the provision of sectional mold 20 members in pairs adapted to be interchanged or replaced, pairs having different mold cavities and adapted to receive metal or sand cores, and power means for closing and mechanical means for opening the mold.

25 I attain the above and other objects by the mechanism and features of construction shown in the accompanying sheet of drawings, in which I have chosen as an illustration of my invention, the machine adapted 30 for casting window-weights.

Figure 1 of the drawings, is a partial side elevation of the machine, certain parts being shown in section, the section through the mold being taken on the line A—A of Fig. 2, 35 looking in the direction of the arrows.

Figure 2 is a partial plan view, part of the mold being shown in full, and the remainder in section along the line B—B of Fig. 3.

40 Figure 3 is a side elevation of one end of the machine, showing the mold members and their supports, a portion of the end members being broken away to show the coil-spring compressed.

45 The numeral 1 throughout the drawings, represents the frame or foundation of my machine, which in this instance is of I beam construction, and upon which is secured at one end a power unit 2, this unit being 50 preferably a cylinder 3 with the usual piston and rings 4, the piston being operable on one side by power means, such as pneumatic or hydraulic pressure controlled by the three-way valve 5. On the opposite end of the 55 cylinder is a vacuum and relief valve 5'.

To the opposite end of the frame are fix-

edly secured standards 6, for supporting a flanged cross-member as the channel 7, and to which are suspendedly secured by the lug 8 and bolt bearing on the facing spot 8', a series of half mold sections 9. A similar series 9' completing the mold paper is similarly suspended and secured, but its channel member 7' is supported on movable standards 10, the base of the latter being rollers 11, positioned within close proximity of its mold members.

Secured midway in the channel 7' as at 12, is the piston-rod head 13, to which is adjustably secured the piston rod 14 as at 15.

The end members 16 of the mold, are recessed at the top and bottom on their meeting faces as at 17, for the housing of coil-springs 18 for a purpose to be presently described. Concentric within the said recesses are provided long dowel pins 19, which are threaded at the head end as at 20 for fixed engagement with the movable half of the mold. The dowel, it will be observed, is concentric with the coil spring 18 also, and 80 slidably moves therethrough as well as through the stationary mold half.

At the top of each half mold, the channel gate 21 for the reception of the molten metal, is secured as at 22 to as many mold 85 sections as is desired.

The cavities 23 shown in the molds are for the formation of window-weights. Near the bottom of each cavity are pins 24 for coring the eyelet of the weight, and may be 90 of chilled-iron or sand, and have conical meeting ends as shown in Fig. 1. The mold sections and channel gate are also preferably of chilled-iron.

95 The mold sections 9 and 9' are similar and interchangeable and replaceable. On the side faces of each mold section, are cored recesses 25 the full length, forming, when the series are put together an air space on both sides of each cavity for venting the 100 heat radiation. Also, it will be observed that the thickness of metal between the cavities and surrounding the cavities is substantially the same. This is for the purpose of radiating the heat from the molten castings 105 equally and uniformly and immediately to the back, thus causing no stresses tending to buckle and warp the mold. Also, the mold being in sections further tends to minimize warping.

110 The sides of the mold sections are quite freely exposed, for the allowance with ease

of the introduction of cores to the mold cavities.

In the operation of the machine, the meeting faces of the bipartite mold are first observed to see if clean and free, then the three-way valve 5 is opened to apply the pressure means on the piston 4 to close the mold as shown in the drawings, for and during the pouring process. The pouring being completed, the three-way valve is then reversed, and the sudden release of pressure within the cylinder coupled with the reaction of the previously compressed coil-springs 18, cause the movable half of the mold to separate at the parting line sufficiently for the castings and gate to drop out thereof and to the unobstructed space beneath, the said movable half riding on the wheels 11 and guided by the dowels 19 and piston-rod 14.

In the drawings, I have shown an embodiment of my invention, but it is to be understood that the invention may be embodied in other forms, each being a species of my invention, and the patent protection that I desire, is all of that which comes within the spirit and scope of what I claim as new, and which claims are the following:

1. As an element of a casting machine, a mold section having a cavity on one face and recesses on its side faces at the parting line of the mold, such, that when similar sections are positioned side by side a vent shaft will be formed centrally between the castings for the escapement of heat radiation.

2. In combination in a casting machine, a mold section and a channel cross-member, the section having a cavity on one face and on its opposite face a central facing-spot and a lug projecting from said face above said

spot, the lug and spot adapted to engage the 40 said cross-member for support in suspension in said machine, and a bolt for holding said mold to said cross-member.

3. In a casting machine, a bipartite mold having recesses on its meeting faces for housing coil-springs, the latter adapted to force the faces apart when external pressure is released on the mold.

4. In a casting machine, a bipartite mold having recesses on its meeting faces for housing coil-springs, dowel pins extending through said mold and springs, the latter adapted to force one part of the mold away from the other guided by said pins.

5. A casting machine comprising a bipartite mold consisting of a series of intermediate mold sections and end sections, the latter sections having recesses on its meeting faces housing coil springs therein, dowel pins extending through said end sections and springs and secured to one part of the said mold, one part of said mold being secured to a transverse channel member, the ends of which adapted to be supported on fixed standards, the other part of said mold also supported on a transverse channel member the ends of which adapted to be supported on movable standards having wheels to allow said movable mold part to travel in a parallel and longitudinal direction, a piston rod 70 fixed to the channel member of said movable mold, a piston on the opposite end of said rod adapted to reciprocate in a cylinder, and means for applying pressure on said piston to force the molds together against the pressure of said springs.

WALTER J. CHRISTIE.
